CIRCUIT BREAKER

Merrill G. Leonard, Sharon, Pa., assignor to Westinghouse Electric & Manufacturing Company, East Pittsburgh, Pa., a corporation of Pennsylvania

Application October 9, 1936, Serial No. 104,842

21 Claims. (Cl. 200—116)

My invention relates to apparatus for interrupting electrical circuits, in general, and more particularly to circuit breaker structures of the protective type which include one or more electro-responsive trip devices for automatically effecting the opening of the contact means of the circuit breaker in response to predetermined overload conditions in the circuits controlled by the breaker.

10 In circuit breakers of the above mentioned type, the electro-responsive device for effecting opening of the contact means in response to overload conditions usually consists of an electromagnetic or bimetallic device or both, connected in series circuit with the contact means of the breaker so as to be responsive to predetermined values of current flowing in the circuit controlled by the breaker. When such circuit breakers are installed for use in electrical systems, they are often called upon to interrupt circuits including highly inductive loads and are often subjected to heavy overloads or to short circuit conditions. In opening a circuit breaker under such conditions, it is well known 15 that current continues to flow therethrough for an appreciable length of time after separation of the contacts due to the formation and persistence of an arc at the contacts. Arc extinguishing devices are usually provided for extinguishing the arc thus formed as quickly as possible. In spite of the provision of such devices, however, the current continues to flow for a length of time sufficient in many instances to damage or destroy the trip devices of the 20 breaker.

It is, therefore, the primary purpose of my invention to provide circuit breakers of the above-mentioned type with a means for protecting the electro-responsive trip device or devices from arc currents.

Another object of my invention is to provide a means for excluding the electro-responsive trip device of the circuit breaker from the circuit of the arc and contacts as soon as the contacts start to open.

Another object of my invention is to provide a circuit breaker with novel internal circuit connections for protecting the trip device of the breaker from excessive currents.

50 Another object of my invention is to provide a circuit breaker having an arc extinguishing means with novel internal circuit connections including a part of said arc extinguishing means for excluding the trip device of the breaker from

the circuit of the arc upon initial separating movement of the contacts.

Another object of my invention is to provide a circuit breaker with means for protecting the trip device thereof by immediately transferring the arc circuit formed incident to the separation of the contacts to an auxiliary contact not included in the circuit of the trip device.

Another object of my invention is to provide a means for protecting the trip device of a circuit breaker by transferring the arc circuit formed incident to separation of the main contacts to an auxiliary contact not included in the circuit of the trip device; in which the auxiliary contact constitutes a part of the arc extinguishing means.

The novel features that I consider characteristic of my invention are set forth in particular in the appended claims. The invention itself, however, both as to structure and operation, together with additional objects and advantages thereof, will best be understood from the following detailed description of specific embodiments thereof when read in connection with the accompanying drawing, in which:

Figure 1 is a vertical sectional view of a circuit breaker embodying the features of my invention.

Fig. 2 is a diagrammatic view illustrating one form of electrical connections for the various elements of the breaker for carrying out the purposes of my invention.

Fig. 3 is a diagrammatic view similar to Fig. 2 illustrating a slightly modified form of apparatus and electrical connections for carrying out the purposes of my invention; and,

Fig. 4 is a plan view of the arc extinguishing device associated with the contacts of the circuit breaker.

In the accompanying drawing, the invention has been shown applied to one particular form of circuit breaker structure embodying an electro-responsive trip device and an arc extinguishing means of the spaced plate type. The particular circuit breaker structure shown was selected for illustrative purposes only and it will readily appear from the following detailed description that the invention is not limited in its application to any one particular circuit breaker structure but that it is capable of association with any form of circuit interrupting device embodying an electro-responsive trip device and an arc extinguishing device.

The circuit breaker illustrated in Fig. 1 is of the same general mechanical structure as disclosed in the United States Patent No. 2,044,157, 55

granted to H. D. Dorfman and John H. Shuler and assigned to the assignee of this invention; hence only a brief description of the same will be given in this application.

- 5 Referring to Fig. 1, the base 1 of the circuit breaker is of molded insulating material and has mounted in recesses provided therein the end terminals 9 and 11, a main stationary contact 13, a movable contact 15, the circuit breaker 10 operating mechanism indicated generally at 17, an electro-responsive trip device 19 and an arc extinguishing means indicated generally at 21. An operating handle 23 also of molded insulating material is provided for actuating the operating mechanism 17. The trip device 19 is supported on the base 1 and positioned with respect to the operating mechanism by means of two suitable screws 25 (only the front screw being shown) which engage threaded inserts 26 molded in the base 1. These screws also serve to connect the trip device in the internal circuit of the breaker which will be described hereinafter. The arc extinguishing means and the operating mechanism are secured to the base in any suitable manner as for example by the screws 27 which extend through suitable openings therein. A cover 29 of molded insulating material is removably mounted on the base by means of bolts (not shown).
- 30 The main stationary contact 13 is mounted on a metallic plate 31 which will hereinafter be termed an arc runner. The arc runner is secured to the base by any suitable means such as one of the screws 27.
- 35 Both the movable and stationary contacts are constructed of arc resisting material, the former being composed of a silver molybdenum alloy and the latter being composed of finely divided silver and graphite compressed into a conglomerate mass. The arc runner 31 may also be constructed of an arc resisting conducting material similar to the stationary contact 13.

40 The movable contact 15 has a channel shaped frame 33 which is pivotally supported on a U shaped main frame 35 of the circuit breaker operating mechanism 17 through the agency of a pivot pin 37. The movable contact 15 is rigidly affixed by means of a rivet to the free end of a resilient switch arm 39 which is preferably constructed of spring steel. The switch arm itself is affixed to the channel shaped frame 33 by means of two other rivets.

45 The operating mechanism 17 comprises in general, the U shaped base or main frame 35, a pair of toggle links 41 and 43 for actuating the channel shaped frame 33 of the movable contact 15, a releasable trigger 45 for restraining the toggle links in an operative position, an operating member 23, and a pair of overcenter springs 50 47 (only one being shown) for connecting the operating member to the knee pivot of the toggle links 41 and 43. The operating member 23 has a bifurcated portion 49, the legs of which are pivotally mounted on the sides of the main frame 55 35 through the agency of pivot pins 51. The releasable trigger 45 is pivotally mounted at one end to the sides of the main frame 35 by means of a pivot pin 53 and has a projecting portion 54 adapted to be normally engaged and held by the 60 trip device 19. The operating member 23 has a hook portion 55 secured to the underside thereof which is adapted to engage a shoulder 57 formed on the trigger 45 for resetting the trigger after the release of the same by the trip device. The lower end of the toggle link 41 is pivoted to the

channel shaped frame 33 by means of a pivot pin 59. The upper end of the toggle link 41 is pivotally connected by means of the knee pivot pin 61 with the lower end of the toggle link 43, the upper end of which is, in turn, pivotally connected to the trigger member 45 through the agency of a pin 63. The overcenter springs 47 have their lower ends connected to the knee pivot pin 61 and their upper ends secured to lugs 64 formed on the underside of the bight of the 10 bifurcated portion 49 of the operating member 23. The trigger 45 provides a releasable restraining means for holding the toggle links in an operative position when the contacts 13 and 15 are engaged.

15 The movement of the trigger member 45 in a clockwise direction is limited by a projection 65 which extends inwardly from one side of the main frame 35. The limits of motion of the bifurcated portion 49 of the operating member 20 23 are defined by the edges 67 of offset portions of the side walls of the main frame 35. A handle portion of the operating member 23 projects through a slot 69 provided in the cover 29.

25 The trip device 19 comprises a U shaped current carrying bimetallic trip element 71. A latch plate 73 is mechanically fastened to the upper end of the trip element 19 and insulated therefrom by means of mica plates 75, the latch plate being held in position by two spaced rivets 30 77 (only one being shown) which extend through a retaining plate 79 and enlarged openings in the top portion of the bimetallic trip element itself. The trip element is supported upon its own terminals 80 (only one being shown) 35 through the agency of rivets 78. The projecting portion 54 of the trigger 45 is normally adapted to be engaged under the lower edge of the latch plate 73 between the rivets 77.

40 The arc extinguishing means 21 consists of a plurality of spaced plates 81 of magnetic material each insulated from the adjacent plates and provided with a slot 83. The slots in the plates are of substantially the same outline as the movable contact 15 and the position of the plates 45 is such that the slots form a path adapted to be traversed by the movable contact 15 in moving into and out of engagement with the stationary contact 13. The plates 81 are assembled between two side walls 85 of insulating material. 50 Projecting lugs 87 are provided on the plates 81 for engagement in openings in the side walls 85.

45 When the movable contact 15 moves away from its engagement with the stationary contact, toward open circuit position, an arc is drawn which creates a magnetic field surrounding the path of the arc. The magnetic plates 81 so unbalance the field adjacent the arc that the arc is moved into the spaces between the plates where it is quickly cooled and extinguished. The plates 60 cause the arc to be immediately transferred from the stationary contact 13 to the arc runner 31 thus protecting the stationary contact from damage by contact with the arc. The arc is split up into a series of short arcs between the adjacent 65 plates 81, the first short arc being immediately established between the arc runner 31 and the bottom plate of the stack.

70 The operation of the circuit breaker will now be briefly described. In Fig. 1, the breaker is shown in the open circuit position with the trigger or restraining member 45 in the set or latched position in which it is held by the latch plate 73 of the trip element 71. The toggle links 41-43 are in their collapsed position. It will be noted 75

that the trigger 45 is at all times biased in a clockwise direction by the reaction force of the overcenter springs 47. Let it be assumed that it is desired to manually close the circuit breaker. 5 The operating member 23 is moved from the position shown in a clockwise direction about its pivot pin 51. Shortly before the operating member has reached the limit of its travel in a clockwise direction, the line of action of the over- 10 center springs 47 is brought to the right of the center line of the toggle. This results in producing a force which automatically moves the toggle links with increasing acceleration to their overset position which effects movement of the 15 movable contact 15 to the closed circuit position with a snap action. To open the contacts, the operating member 23 is moved from its closed circuit position in a counter-clockwise direction about its pivot pin 51 to its open circuit position 20 shown in Fig. 1. Substantially the reverse action takes place. The line of action of the overcenter springs is moved to the left of the center line of the toggle which produces a force which automatically moves the toggle links with in- 25 creasing acceleration to their collapsed position shown in Fig. 1. The collapsing of the toggle causes movement of the movable contact 15 to its open circuit position with a snap action.

The bimetallic trip element 71 is adapted to 30 be connected in series circuit with the contacts of the breaker as will be described hereinafter. With the circuit breaker in the closed circuit position; upon the occurrence of an overload condition of predetermined magnitude, the increased 35 I^2R loss in the bimetallic trip element results in the production of sufficient heat to cause that element to deflect in a direction away from the operating mechanism 17. If the overload persists for a sufficient length of time, this deflection be- 40 comes great enough to move the latch plate 73 out of latching engagement with the projecting portion 54 of the trigger 45. This unlatching of the trigger 45 allows that member to rotate in a clockwise direction about its pivot pin 53 under the influence of the reaction forces of the over- 45 center springs 47. Almost immediately the upper end of the toggle link 48 which is pivoted to the trigger 45 by the pin 63, is moved a sufficient distance to the right of the center line of the toggle to cause the toggle to collapse under 50 the influence of the overcenter springs 47 exerting their tension on the knee pivot pin 61. The channel shaped frame 33 is rotated about its pivot pin 37 by the collapse of the toggle, thus moving the movable contact 15 to its open circuit position with a snap action in the same manner as described for the manual operation.

Following the tripping operation and the resulting change in position of the knee pivot pin 61, the operating handle 23 is biased in a counter-clockwise direction but moves only to a mid-position in the slot 69 of the cover 29. This movement of the handle 23 to the mid-position following the tripping operation serves as 5 a ready indicating means for showing that the circuit has been opened in response to an abnormal electrical condition.

The entire mechanism is resettable after a tripping operation by movement of the operating 0 member 23 to the full open circuit position as soon as the bimetallic trip element 71 has cooled sufficiently to restore the latch plate 73 to the position shown in Fig. 1. This movement causes the hook portion 55 of the operating member to 5 engage and move the trigger member 45 in a

counter-clockwise direction until its projecting portion 54 reengages under the latch plate 73. The breaker may then be closed manually in the manner previously described.

The operating mechanism 17 is trip free of the 5 operating member 23 in any position of the parts, i. e., the movable contact 15 may be tripped to the open circuit position irrespective of the position of the operating member 23.

It has been the practice in most circuit breakers 10 of the above-mentioned type to connect the electro-responsive trip device or bimetallic trip element in series circuit relationship with the contact means of the breaker in order that the device may respond to overload conditions. 15 When the breaker having the above-mentioned connection is manually operated to open a circuit including a highly inductive load, or when it is automatically opened in response to an ab- 20 normally large overload or short circuit condition, the persistence of the arc after the separation of the contacts may result in damage or de- 25 struction of the trip device with the resulting loss of the safety feature in subsequent overloads.

The means for protecting the electro-respon- 25 sive trip device from the damage indicated above will now be described.

The electro-responsive trip device or the bi- 30 metal trip element in the present disclosure is pro- 35 tected from abnormal current conditions by means of novel internal circuit connections for connecting the trip device in a certain circuit relationship with the terminals, contact means and a part of the arc extinguishing means. In one form of the invention, the connections are 40 made as follows: Referring to Fig. 2, a con- 45 ductor 89 connects the load terminal to the rear terminal 82 of the bimetallic trip element 71. The forward terminal 80 of the trip element 71 is connected directly to the arc runner 81 and sta- 50 tionary contact 13 by means of an insulated con- 55 ductor 91. The movable contact 15 is connected through the agency of the switch arm 39 with an insulated conductor 93, which is, in turn, connected to the line terminal 11 of the circuit 60 breaker. The conductor 93 is electrically connected to the line terminal 11 by means of the terminal connector screw 94. (See Fig. 1.) It will be noted that the connections described above place the bimetallic trip element 71 in 65 series circuit relationship with the stationary contact 13, the movable contact 15, and the end terminals 9 and 11 of the circuit breaker when the contacts are closed. The insulated shunt conductor 95 connects the back terminal 82 to 70 the bimetallic trip element 71 with the bottom plate 81 of the arc extinguishing means 21. The conductors 91 and 95 are connected to the terminals of the bimetallic trip element through the agency of the screws 25. The insulated con- 75 ductor 91 is connected to the stationary contact 13 and arc runner 81 through the agency of a screw 92 (see Fig. 1). A recess 96 is provided in the base 7 of the circuit breaker for receiving the insulated conductor wires 91, 93 and 95 (see Fig. 80 1). The operation of the breaker with the form of connections described above is as follows:

With the contacts in the closed circuit position, the circuit through the breaker extends from the line terminal 11 through the conductor 93, the switch arm 39, movable contact 15, stationary contact 13, insulated conductor 91, the front terminal 80 of the bimetallic trip element 71, the bimetallic trip element 71, the back terminal 82 of the trip element and the conductor 89 to the 85

load terminal 8. If the movable contact 15 is moved toward open circuit position either in response to operation of the operating member 23 or in response to a tripping operation by 5 means of the bimetallic element 71, an arc is formed between the contact 13 and the movable contact 15. The arc is immediately transferred from the stationary contact 13 to the arc runner 31 by the unbalanced magnetic field caused by 10 the plates 31. As has been previously described, the arc is split up into a series of short arcs extending between the plates 31 and between the bottom plate 31 and the arc runner 31. The short arc between the arc runner 31 and the bottom plate 31 of the stack is sustained only by the 15 voltage drop across the bimetallic trip element 71. This voltage is so low that the short arc between the bottom plate 31 and the arc runner 31 is immediately extinguished, thus excluding the bimetallic trip element from the circuit of the 20 remaining arc or arcs. The arc circuit then extends from the load terminal 8 through the conductor 95 to the bottom plate 31 of the stack through the arc in the space between the plates 25 to the movable contact 15 and through the conductor 93 to the line terminal 11. It will thus be seen that the bimetallic trip element is excluded from the circuit of the arcs as soon as the movable contact moves a sufficient distance to establish 30 an arc either between the stationary contact and the bottom plate or between the arc runner and the bottom plate 31 of the arc extinguishing means. Hence the arc current can have no damaging effect on the bimetallic trip element. If 35 the voltage drop across the bimetallic trip element should be too high, more than one of the arc extinguishing plates could be included between the arc runner and the bimetallic connector 33.

40 A slightly modified form of arc extinguishing means and circuit connections for accomplishing the purposes of the invention are shown in Fig. 3. In Fig. 3, the arc runner is divided into two sections 31 and 32. The insulated conductor 93 which is connected to the back terminal of the bimetallic trip element 71 instead of being connected to the bottom magnetic plate 31 as in Fig. 2, is connected to the end section 32 of the arc runner. All of the other electrical connections 45 and elements are the same as the corresponding connections and elements shown in Figs. 1 and 2. The operation of this modified form of apparatus and circuit is similar in principle to the embodiment shown in Figs. 1 and 2. When the 50 movable contact is in the closed circuit position, the electro-responsive trip device or bimetallic trip element 71 is connected in series circuit relationship with the contacts 13 and 15 through the following circuit: Line terminal 11, insulated conductor 93, switch arm 39, movable contact 15, stationary contact 13, insulated conductor 91, bimetallic trip element 71, conductor 39 and load terminal 8. As soon as the movable contact starts to move to the open circuit position either 55 in response to a manual or a tripping operation, the arc formed at the contacts is transferred to the extreme end section 32 of the arc runner by the unbalanced magnetic field produced by the plates 31. The end section 32 of the arc 60 runner constitutes, in effect, an auxiliary contact to which the arc is transferred as soon as the movable contact starts to move to the open circuit position. As soon as the arc is transferred to the end section 32 of the arc runner, the electro- 65 responsive trip device or bimetallic trip element 75

71 is excluded from the circuit of the arc by means of the insulated shunt conductor 95. The arc circuit then extends from the load terminal 8 through conductor 89 and the insulated shunt conductor 95 to the end section 32 of the arc 5 runner, through the stack of plates, the movable contact 15, through the switch arm 39 and the insulated conductor 93 to the line terminal 11.

It will be noted that in the embodiment shown by Figs. 1 and 2, the bottom magnetic plate of 10 the arc extinguishing means constitutes, in effect, an auxiliary contact to which the arc is transferred upon initial movement of the movable contact toward its open circuit position.

An important feature of the invention lies in 15 the fact that the current-responsive element is shunted out of the circuit as soon as the moving contact has moved only a short distance and before it has moved to the full open position. This removes the current-responsive element 20 from the circuit before it has time to heat up and burn out. It is also advantageous that the circuit of my device does not require a connection to the top arc extinguishing plate which would impress line voltage across the arc extinguisher 25 even when the circuit is open and would permit a leakage current to flow if the fibre side plates of the arc extinguisher should become damp or carbonized.

While the invention has been shown associated 30 with a particular form of circuit breaker, it is obvious that the invention is equally applicable to any form of circuit interrupting device which includes an electro-responsive trip device and an arc extinguishing means or arc moving means. 35 For example, the various forms of electro-responsive trip devices may be substituted for the U-shaped bimetallic trip element illustrated. The trip device may be either in the form of a thermally responsive device or in the form of an electromagnetic trip device. Likewise, various other forms of arc extinguishing devices may be used. The arc extinguishing means illustrated is merely selected for simplicity to illustrate the principle of the invention. One particularly effective form 40 of arc extinguishing means to which the invention is applicable is disclosed in the United States Patent No. 1,963,643 granted to Benjamin P. Baker and Maurice W. Brainard, and assigned to the assignee of this invention. 50

It will thus be seen that I have provided a novel means associated with a circuit interrupting device of the protective type for protecting the electro-responsive trip device thereof from damage by the arc current. 55

While in accordance with the provisions of the patent statutes, I have disclosed the foregoing details of several embodiments of my invention, it is to be understood that many of the details are merely illustrative and that variations, in addition to those mentioned, in their precise form may be made without departing from the spirit of the invention. I desire, therefore, that the language of the accompanying claims shall be accorded the broadest reasonable construction, 60 and that my invention be limited only by what is explicitly stated in the claims and by the prior art. 65

I claim as my invention:

1. A circuit interrupting device comprising 70 switch contacts, electro-responsive means for effecting separation of said contacts connected in circuit therewith, arcing plates to which the arc between the contacts is transferred, and means for shunting the arc current around said electro- 75

responsive means and one of said contacts to one of said arcing plates upon initial opening movement of said switch contacts.

2. A circuit interrupting device comprising 5 switch contacts, electro-responsive means for effecting separation of said contacts connected in circuit therewith, arcing plates, means including said plates for effecting transfer of the arc from said contacts to said plates and connections 10 rendered operable by transfer of the arc for excluding said electro-responsive device from the circuit of the arc as soon as said contacts have separated a small part of their total distance of separation.

15 3. A circuit breaker comprising a stationary contact, a movable contact, electro-responsive means for effecting movement of the movable contact to open circuit position connected in circuit with said contacts, means including a series 20 of spaced plates of magnetic material for transferring the arc formed incident to the opening of the contacts from the contacts to said plates and for extinguishing the same, and a connection completed by the arc for excluding said electro-responsive device from the circuit of the arc 25 during the first part of the movement of said movable contact toward open circuit position.

4. A circuit breaker comprising switch contacts, electro-responsive means connected in circuit with said contacts for effecting opening of 30 said contacts in response to predetermined conditions, means including a series of spaced plates of magnetic material for effecting transfer of the arc formed incident to the opening of said contacts from the contacts to said plates, and means 35 operable by transfer of the arc for excluding the electro-responsive device from the circuit of the arc upon the initial opening movement of said contacts.

40 5. In a circuit breaker the combination of a stationary contact, a movable contact, an electro-responsive device connected in the circuit leading to the stationary contact for effecting movement of the movable contact to the open circuit position in response to predetermined conditions, an arc extinguishing device comprising an arc runner connected to the stationary contact and a plurality of spaced notched plates of magnetic material for transferring the arc formed incident to the opening of the contacts from said contacts to said arc runner and said plates, a connection from said electro-responsive device to one of said plates nearest said stationary contact for excluding said electro-responsive device 50 from the circuit of the arc as soon as said movable contact has moved a small part of its total movement to the open circuit position.

6. A circuit interrupting device comprising a fixed and a movable contact between which an arc is drawn, an electro-responsive device connected in circuit with said contacts for effecting movement of the movable contact to open circuit position in response to a predetermined magnitude of current, means including a plurality of 65 arcing plates of magnetic material for effecting transfer of the arc from said contacts to said plates, and a connection from said electro-responsive device to one of said plates for excluding said device from the circuit of the arc upon initial movement of said movable contact toward open circuit position.

7. A circuit breaker comprising a stationary and a movable contact between which an arc is drawn, an electro-responsive device connected in 75 circuit with said contacts for effecting movement

of the movable contact to the open circuit position in response to a predetermined condition, an auxiliary contact, means for excluding said device from the circuit of the arc and for transferring the arc to said auxiliary contact upon initial movement of said movable contact toward open circuit position. 5

8. A circuit breaker comprising a stationary contact and a movable contact between which an arc is drawn, an electro-responsive trip device 10 connected in the circuit leading to the stationary contact for effecting opening of said contacts, an arc extinguishing means including a series of spaced notched plates of magnetic material for transferring the arc from said contacts to said 15 plates and a connection for excluding said device and said stationary contact from the circuit of the arc upon movement of the movable contact toward open circuit position.

9. In a circuit breaker the combination of 20 switch contacts, electro-responsive means connected in circuit with said contacts for effecting separation of said contacts in response to predetermined conditions and means for excluding the electro-responsive device from the circuit of the 25 arc formed incident to separation of the contacts, said means being operable in response to the initial separating movement of the contacts.

10. In a circuit breaker the combination of 30 switch contacts, a thermal bimetallic device in circuit with said contacts for effecting separation of said contacts in response to predetermined conditions, and means for excluding the thermal bimetallic device from the circuit of the arc 35 formed incident to the separation of said contacts, said means being operable in response to the separation of said contacts and as soon as said contacts have separated a small part of their total distance of separation.

11. In a circuit breaker the combination of 40 line and load terminals, a stationary contact, a movable contact connected to said line terminal, an electro-responsive device having one terminal thereof connected to the load terminal and its other terminal connected to said stationary contact for effecting movement of the movable contact to open circuit position in response to predetermined conditions, an arc extinguishing means comprising an arc runner connected to said stationary contact and a series of notched 45 spaced plates of magnetic material for effecting transfer of the arc formed incident to separation of the contacts from the stationary contact to said arc runner and said plates and a connection completed by the transfer of the arc to said arc 50 runner for excluding said electro-responsive device from the circuit of the arc as soon as the movable contact has moved a small part of its total movement toward open circuit position. 55

12. In a circuit breaker the combination of 60 line and load terminals, a stationary contact, a movable contact connected to said line terminal, an electro-responsive device having one terminal thereof connected to the load terminal and its other terminal connected to said stationary contact for effecting movement of the movable contact to open circuit position in response to predetermined conditions, an arc extinguishing means comprising an arc runner connected to said stationary contact and a series of notched spaced 65 plates of magnetic material for effecting transfer of the arc formed incident to separation of the contacts from the stationary contact to said arc runner and said plates and a connection from the load side of said electro-responsive device to one 70 75

of said plates for excluding said device from the circuit of the arc upon initial movement of said movable contact toward open circuit position.

13. In a circuit breaker the combination of line and load terminals, a stationary contact, a movable contact connected to one of said terminals, an electro-responsive device having one terminal thereof connected to the other terminal and its other terminal connected to said stationary contact for effecting movement of the movable contact to open circuit position in response to predetermined conditions, an arc extinguishing means comprising an arc runner connected to said stationary contact and series of notched spaced plates of magnetic material for effecting transfer of the arc formed incident to separation of the contacts from the stationary contact to said arc runner and said plates and a conductor connecting the first mentioned terminal of said device to the plate nearest said arc runner for excluding said device from the circuit of the arc as soon as said movable contact has moved a small part of its total movement toward open circuit position.
14. In a circuit breaker the combination of line and load terminals, a stationary contact, a movable contact connected to said line terminal, a bimetallic device having one terminal thereof connected to the load terminal and its other terminal connected to said stationary contact for effecting movement of the movable contact to open circuit position in response to predetermined conditions, an arc extinguishing means comprising an arc runner connected to said stationary contact and series of notched spaced plates of magnetic material for effecting transfer of the arc formed incident to separation of the contacts from the stationary contact to said arc runner and said plates and a connection for excluding said bimetallic device from the circuit of the arc operable in response to the initial movement of said movable contact toward open circuit position.
15. In a circuit breaker the combination of switch contacts, a bimetallic device in circuit with said contacts for effecting separation of said contacts in response to predetermined conditions, and means including a circuit completed by the arc formed incident to the separation of the contacts for excluding the bimetallic device from the circuit of the arc as soon as said contacts have separated a small part of their total distance of separation.
16. In a circuit breaker the combination of line and load terminals, a movable contact connected to the line terminal, a stationary contact, an electro-responsive means having one terminal connected to the load terminal and its other terminal connected to said stationary contact for effecting movement of said movable contact to open circuit position in response to predetermined condition, an arc extinguishing device comprising a divided arc runner having one section thereof connected to the stationary contact, the other section thereof insulated therefrom, a plurality of notched spaced plates of magnetic material for effecting transfer of the arc formed incident to separation of the contacts from said stationary contact to the insulated section of the arc runner and to said plates, and a connection from the first mentioned terminal of said electro-responsive means to said insulated sec-

tion of the arc runner for excluding said electro-responsive means from the circuit of the arc upon initial movement of said movable contact toward open circuit position.

17. In a circuit breaker the combination of line and load terminals, a movable contact connected to the line terminal, a stationary contact, a bimetallic means having one terminal connected to the load terminal and its other terminal connected to said stationary contact for effecting movement of said movable contact to open circuit position in response to predetermined condition, an arc extinguishing device comprising a divided arc runner having one section thereof connected to the stationary contact, the other section thereof insulated therefrom, a plurality of notched spaced plates of magnetic material for effecting transfer of the arc formed incident to separation of the contacts from said stationary contact to the insulated section of the arc runner and to said plates, and a connection from the first mentioned terminal of said bimetallic means to said insulated section of the arc runner for excluding said means from the circuit of the arc as soon as said movable contact has moved a small part of its total movement toward open circuit position.

18. In a circuit breaker the combination of a stationary contact, a movable contact, an electro-responsive device normally connected in circuit with said contacts for effecting movement of the movable contact to open circuit position in response to predetermined overload conditions, an auxiliary conducting member to which the end of the arc established on the stationary contact is transferable and means for excluding said electro-responsive device from the circuit of the arc upon transfer of the end of the arc from the stationary contact to said auxiliary conducting member.

19. In a circuit breaker the combination of a stationary contact, a movable contact, a bimetallic device connected in circuit with the stationary contact for effecting movement of the movable contact to open circuit position in response to predetermined overload conditions, means for transferring the arc formed incident to separation of the contacts from said stationary contact to an auxiliary contact and a conductor connected to said auxiliary contact for excluding said device from the circuit of the arc immediately after said movable contact has moved a small distance toward open circuit position.

20. In a circuit interrupter, the combination of a stationary contact, a movable contact, an electro-responsive device normally connected in circuit with said contacts, a plurality of conducting members into which the arc drawn between said contacts is movable, and one of said conducting members nearest said stationary contact being connected to provide a shunt circuit around said electro-responsive element upon contact of the arc therewith.

21. In a circuit breaker the combination of switch contacts, electro-responsive trip means connected in circuit with said contacts for effecting separation of said contacts in response to predetermined conditions, and means including an electrical connection completed by the arc formed incident to the separation of said contacts for excluding the electro-responsive means from the circuit of the arc upon initial separating movement of the contacts.
